US0D1014213S

(12) **United States Design Patent** (10) **Patent No.:** **US D1,014,213 S**
(45) **Date of Patent:** **** Feb. 13, 2024**

(54) **POWER HAMMER**

(71) Applicant: **Robert Bosch GmbH**, Stuttgart (DE)

(72) Inventor: **Wei Gu**, Zhejiang (CN)

(73) Assignees: **Bosch Power Tools (China) Co., LTD.**,
Zhejiang (CN); **Robert Bosch GmbH**,
Stuttgart (DE)

(**) Term: **15 Years**

(21) Appl. No.: **29/816,206**

(22) Filed: **Nov. 19, 2021**

(30) **Foreign Application Priority Data**

May 21, 2021 (CN) 202130306357.3

(51) **LOC (14) Cl.** **08-05**

(52) **U.S. Cl.**

USPC **D8/69**

(58) **Field of Classification Search**

(57) **CLAIM**

The ornamental design for a power hammer, as shown and described.

DESCRIPTION

FIG. 1 is a right-front perspective view of a power hammer showing my new design;

FIG. 2 is a left-rear perspective view of the power hammer of FIG. 1;

FIG. 3 is a left side elevational view of the power hammer of FIG. 1;

FIG. 4 is a right side elevational view of the power hammer of FIG. 1;

FIG. 5 is a front elevational view of the power hammer of FIG. 1;

FIG. 6 is a rear elevational view of the power hammer of FIG. 1;

FIG. 7 is a top plan view of the power hammer of FIG. 1; and,

FIG. 8 is a bottom plan view of the power hammer of FIG. 1.

The broken lines shown in the drawings depict portions of the power hammer that form no part of the claimed design.

1 Claim, 8 Drawing Sheets
